UNITED STATES PATENT OFFICE.

FREDERICK D. CRANE, OF MONTCLAIR, NEW JERSEY, ASSIGNOR OF ONE-HALF TO
NATHANIEL L. FOSTER, OF MONTCLAIR, NEW JERSEY.

RECEPTACLE CLOSURE.

1,417,975.

Specification of Letters Patent. Patented May 30, 1922.

Application filed April 9, 1921. Serial No. 459,951.

To all whom it may concern:

Be it known that I, FREDERICK D. CRANE, a citizen of the United States, residing at Montclair, in the county of Essex and State 5 of New Jersey, have invented certain new and useful Improvements in Receptacle Closures, of which the following is a specification.

This invention relates to receptacle closures, and it comprises a can or receptacle having an outlet opening, the edge of the opening being formed in the arc of a circle or other curvature, and a head or closure member pivotally mounted on said receptacle and adapted to cover the outlet opening, the upper face of said closure member being curved on a radius less than the radius of the curve formed on the edge of the outlet opening, the closure member being eccentrically mounted with respect to said curved edge.

In the present invention, I provide an improved method of closing collapsible tubes, cans, or boxes, in which tooth paste, shaving 25 soaps, talcum powders, and the like, are packed and which should be tightly closed when not in use, on account of the volatile nature of the constituents. I further provide a closure which will not stick on account 30 of the gummy ingredients often present in the contents of the tubes or cans.

To attain this end, the can or tube is provided with a curved edge at the outlet opening, and a head or closure member is pivotally mounted over the outlet opening and is provided with an upper surface curved on a slightly less radius. The closure member is mounted eccentrically to the curvature of the can top, whereby it is easily moved from the closed to the open position, but when returned to the closed position, it engages the curved edge and then binds against the curve or slope. The closing action incidentally wipes the surface of the outlet opening clean, and is maintained in closed position by friction.

In the accompanying drawings, I have shown one embodiment of the invention. In this showing:

50 Figure 1 is a side elevation with the closure member in closed position,

Figure 2 is a similar view, parts being shown in section, with the closure member in open position,

55 Figure 3 is a detail perspective view of

the closure member and a supporting ring therefor, and,

Figure 4 is a similar view of an alternate form of supporting member.

Referring to the drawings, the reference 60 numeral 1 designates the container which may be a can, tube, or other receptacle of the type generally employed for packing tooth pastes, shaving powder, and talcum powders, or the like. The container is provided with a neck 2, having an outlet opening 3. As shown, the edge of the outlet opening is curved in the arc of a circle or other curvature. The center of the arc of the outlet opening is designated at 4. 70

A closure member 5 is pivotally mounted on the neck of the container, the pivot thereof being arranged slightly eccentric to the center of the curve 3, as shown at 6. The upper face of the member 5 is curved on the 75 radius slightly less than the curvature of the outlet opening. The closure member is provided with a pair of ears or lugs 7, by means of which it is pivotally mounted on the neck of the container. A finger piece 8 80 is provided to permit opening and closing of the closure member. The ears are provided with openings 9, for the reception of pins or other fastening members.

A supporting ring 10 is suitably arranged 85 on the neck of the container, and this ring is provided with oppositely disposed lugs or ears 11, having openings 12. The openings 9 and 12 are adapted to register with each other and to receive pivot pins to pivotally 90 support the closure member.

In Figure 4 of the drawings, I have shown an alternate form of supporting member, comprising a wire ring 13, having loops 14, for the reception of pivot pins. The ends 95 of the wire are twisted, as at 15, to retain it in position.

The closure member may be made of any suitable material, preferably of the same material as the tube or can, or other material which will not be attacked by the contents of the can. The supporting device may be secured on the neck of the container, in any suitable manner. A layer of cork or other suitable material (not shown) may be 100 arranged on the inner face of the closure member, when the contents of the container are particularly liquid or volatile.

It is to be understood that the form of my invention herewith shown and described 110

is to be taken as a preferred example of the same, and that various changes in the shape, size, and arrangement of parts may be resorted to without departing from the spirit 5 of the invention or the scope of the subjoined claims.

Having thus described my invention, I claim:

1. The combination with a receptacle having an outlet opening, the edge of which is curved, of a closure member comprising a curved plate adapted to cover said opening, the curvature of said plate being on a smaller radius than the curvature of the edge 15 of the opening, a pair of downwardly projecting ears carried by said plate, a ring arranged around the receptacle, said ring being provided with ears, the ears of said plate being pivotally connected to the ears 20 of said ring, and said pivots being arranged eccentrically of the center of said curved edge.

2. The combination with a receptacle having an outlet opening, the edge of which is 25 curved, of a closure member comprising a

curved plate adapted to fit over the outlet opening, the curvature of the plate being on a smaller radius than the curvature of the edge of the opening, and means for pivotally mounting said closure member eccentrically of said curved edge. 30

3. The combination with a receptacle having an outlet opening, the edge of which is curved, of a closure member comprising a curved plate adapted to cover said opening, 35 the curvature of said plate being on a smaller radius than the curvature of the edge of the opening, a pair of downwardly projecting ears carried by said plate, whereby the closure member is pivoted to the receptacle, the pivots of said closure member being arranged eccentrically of the center of said curved edge. 40

In testimony whereof I affix my signature in presence of two witnesses.

FREDERICK D. CRANE.
